SUCTION CLEANER

Bernard C. Becker, Canton, Ohio, assignor to The
Hoover Company, North Canton, Ohio, a cor-
poration of Ohio

Application March 18, 1938, Serial No. 196,648

7 Claims. (Cl. 15—9)

This invention relates to improvements in suction cleaners and more particularly to a suction cleaner designed to be converted to and from off-the-floor cleaning operation with the use of 5 dusting tools and with the added feature of an arrangement whereby the nozzle is raised above its normal height preparatory to the converting operation and thus maintained during the period of dusting tool operation.

10 When cleaners are equipped with carpet contacting agitators or rotary brushes it is desirable to elevate the nozzle while the dusting tools are being used in order to prevent undue carpet wear which might otherwise occur if the cleaner 15 were allowed to stand in one position for a considerable length of time. Furthermore, it is advantageous to design the nozzle raising mechanism in such a way that the conversion for dusting tool operation cannot be completed until the 20 nozzle or forward portion of the cleaner has first been elevated to the safety level.

A simple and common method of raising and lowering the nozzle is to provide either adjustable front or rear wheels, that is to say, wheels 25 that may be adjusted bodily in a vertical direction preferably by mounting them upon pivoted supporting brackets. And, to control the converting operation, a lever arm or barrier is made a part of the adjustable wheel support, said barrier 30 normally acting to prevent the insertion of the converter member into the port provided to receive it. An arrangement embodying the general features herein outlined, is disclosed in an application filed on July 6, 1936, bearing Serial 35 No. 89,062, now Patent 2,142,810, in which the rear wheels form a part of a spring-pressed hinged mounting including a barrier lever coacting with a converter port at one side of the cleaner casing. In this arrangement, it is necessary 40 to press downwardly on the rear portion of the cleaner casing in order to overcome the spring tension and in so doing the barrier lever is displaced below the converter port permitting the converter member to be inserted, whereupon the cleaner casing remains in a slightly tilted position with the nozzle elevated and with the barrier lever in contact with the converter member to hold the nozzle in elevated position until the converter member is removed.

45 The present disclosure differs from the earlier disclosure in a number of particulars, the chief difference being that the front wheels are vertically adjustable instead of the rear wheels, although it is to be pointed out that the invention 50 resides in something more than merely reversing

the adjustability of the front and rear wheels, but rather brings into play a somewhat different load distribution factor, so that it is possible by merely changing the position of the handle, or at least, by slight pressure thereon, to cause the cleaner 5 to tilt backwardly on its rear wheels and simultaneously raise the nozzle and expose the converter port for the insertion of the converter member. It is therefore the object of the present invention to provide an improved arrangement of interlocking coaction between the converting operation and the elevation of the nozzle.

A preferred embodiment of the invention is disclosed in the accompanying drawings, in which:

Figure 1 is a view in side elevation of a suction 15 cleaner with a section of the casing wall removed to show the front wheel mounting with its barrier lever in normal position;

Figure 2 is a bottom plan view of the cleaner 20 body;

Figure 3 is a view in side elevation corresponding to Figure 1, showing the converter member inserted and the nozzle elevated;

Figure 4 is a fragmentary bottom plan view 25 showing the converter member inserted into the converter port; and

Figure 5 is an enlarged perspective view of the 30 front wheel mounting including the barrier lever.

Referring to the cleaner in its general aspects, 35 the same comprises a wheeled casing 1, having a nozzle portion 2 extending transversely of its forward end, with a downwardly opening suction mouth. Within the nozzle and extending lengthwise thereof is a rotary agitator 3 consisting of a cylindric shell having a suitable arrangement of brush elements and helically arranged beater bars, such as are common to agitators of this type.

Located centrally of the casing 1 is a relatively shallow fan chamber 4 enclosing a fan 5 having direct driving connection with a motor (not shown) supported on the top of the casing 1 and enclosed within a cover or dome 6. At the geometric center of the bottom wall of the fan 45 chamber 4 is the circular opening 4a forming the inlet or eye of the fan chamber and communicating with one end of a passage extending forwardly and communicating with the nozzle. This passageway is formed in part by a shallow 50 depending wall 7 extending around the rear half of the fan eye 4a, thence forwardly with a slight outward flare and thence curving abruptly in opposite directions to form the rear wall of the nozzle chamber. A removable bottom plate 8, 55

which also includes the rear lip of the suction mouth, completes the passage. Enclosed within the passage is a belt 9 driving from a pulley extension 10 of the fan hub to a groove at the 5 central portion of the agitator 3.

Thus, the dirt-laden air entering the nozzle through the suction mouth passes through the inlet passage into the fan chamber, thence to be discharged rearwardly and into a dirt bag 11 10 having detachable connection with a rearwardly opening flanged outlet connection 12.

The cleaner is supported upon pairs of front and rear wheels, the front wheels 13, 13 being independently journaled just to the rear of the 15 nozzle portion 2 and in close proximity to the side walls of the casing 4, whereas the rear wheels 14, 14 are preferably combined in the form of a caster, consisting of a bracket 16 having pivotal connection with the underside of the cleaner casing 20 and supporting an axle 15 on which the wheels are journaled. For the purpose of the present disclosure, the rear wheels 14, 14 may be considered as fixed with relation to the cleaner casing, although for practical purposes they are 25 made vertically adjustable in order to vary the height of the nozzle with respect to different types and grades of carpet to be cleaned.

Thus, the cleaner is preferably equipped with a manually operated adjusting mechanism for 30 the rear wheel consisting essentially of a rod 17 attached at one end of the wheel supporting axle 15 and, passing upwardly through the cleaner casing, is surmounted by an adjusting knob 18 accessible by the operator for raising 35 or lowering the rear caster and thus tilting the entire cleaner casing about the front wheels as a fulcrum to obtain the desired setting for the nozzle. However, it is to be understood that the adjustment of the rear wheels has no connection 40 with the raising of the nozzle as a function of the converter operation.

Referring now to the provision made for converting the cleaner from on-the-floor to off-the-floor cleaning operation, the transition from 45 one to the other consists primarily in diverting the incoming air stream from the nozzle to the auxiliary hose carrying the dusting tools. The method of conversion herein employed is a comparatively simple one involving the provision of 50 a port or passage leading into the air inlet passage immediately adjacent the fan eye and adapted to receive a special fitting mounted at one end of the dusting tool hose. The insertion of the converter member or fitting crosswise of 55 the air inlet passage simultaneously closes off the inlet from the nozzle and establishes connection with the hose. Thus, referring to Figures 2 and 4 particularly, on the underside of the cleaner casing is a metal shell 19, generally U-shaped in 60 cross-section and forming the side and bottom walls of a rectangular relatively shallow passage leading from the outer edge of the cleaner casing substantially at right angles and inwardly to the side wall 7 of the inlet passage where a 65 port or opening is formed. As more clearly shown in Figure 4, the opening or port at the inner end of the converter passage is normally closed by a spring-actuated valve or gate member 20, which swings downwardly and into open 70 position upon the insertion of the converter member 21, as shown in Figure 4. Hence, the operation of the converting of the cleaner to off-the-floor cleaning operation, providing no barrier interferes, is simply that of inserting the 75 converter member 21 at the end of the dusting

tool hose 26 endwise into the laterally opening converter passage and thence through the normally closed port and finally into the inlet passage immediately forwardly of the pulley 10. And, as shown in Figure 4, once inserted a spring 5 latching member 21a on the converter member 21 holds the latter in position until released by the pressure of the thumb. So much for the converter arrangement which is more or less typical of one that is now in commercial use. 10

Reference will now be made to the adjustable mounting of the front wheels and the barrier operated by one of them to prevent the conversion operation from being completed without first raising the nozzle above the floor surface. 15 Each of the front wheels 13 are journaled upon stub shafts 13a carried by pivoted supporting brackets 22 having pivotal mounting at the lower end of a vertically disposed post 23 suitably anchored to the underside of the cleaner casing. 20 A transverse bearing pin 24 supports each pivoted wheel supporting bracket 22 and a torsion spring 25 is coiled around each of the bearing pins 24, with one end bearing against an adjacent downwardly facing edge 23a of the post 25 23 as an abutment, and its other end also extending forwardly and hooked over the stub shaft of each wheel 13. The front wheels 13 are thus mounted forwardly of the bearing pins 24 supporting their brackets 22 so that normally 30 said wheels would tend to swing in a counter-clockwise direction under the weight of the cleaner. However, the torsion springs 25 act to counterbalance a part of the load on the front wheels, but it is to be noted that these 35 springs are not strong enough to overcome or even counterbalance the weight normally carried upon the front wheels, with the result that under normal operating conditions, the depression of the front end of the cleaner is limited 40 only by abutting contact between the top edges of the pivoted brackets 22 and the abutment 23a of the supporting posts 23, as clearly shown in Figure 1.

Now, the mounting of both front wheels is 45 identical except for a rearwardly extending lever arm 27 which forms an integral part of the wheel supporting bracket 22 located adjacent the converter passage. This lever arm 27 is a vertically arranged blade-like lever normally assuming a horizontal position immediately below the underside of the fan chamber 4 and also projecting into the converter passage through a slot or opening in the forward upright wall thereof, as clearly shown in Figures 1 and 4. 55 Obviously, with this lever arm extending into the passage, it serves as an effective barrier against the insertion of the converter member until removed. To remove the barrier it is only necessary to tilt the cleaner body backwardly on 60 its rear wheels, thus allowing the torsion springs 25 to depress the front wheels bodily in a clockwise direction from the position shown in Figure 1 to that shown in Figure 3, so that the nozzle portion 2 is not only raised a considerable distance above the floor surface but the barrier lever 27 is swung upwardly and entirely out of the converter passage. It is now possible to insert the converter member with a simple endwise sliding movement. It is obvious however, 70 that the insertion of the converter member is accomplished while the cleaner casing is still in its backwardly tilted position and once the conversion has been completed, the cleaner casing may be allowed to tilt forwardly, but only so far 75

as permitted by the contact of the barrier lever 27 with the converter member. Thus, the cleaner is prevented from resuming its normal position with the nozzle in proximity to the floor surface while the converter member is in place.

In common with suction cleaners of the handle-manuevered type, the present cleaner is equipped with a handle 28 of the usual type and arrangement and of a length such that the operator can readily maneuver the cleaner over the carpet surface from an erect position. The handle is mounted well above the top of the casing 1 and is intended to swing about a transverse axis from a rearwardly extending horizontal position to an upright position, with an intermediate working range. Though not shown, means may be provided for positively locking the handle in its extreme positions with a hand or foot operated release device, or it may have a torsion spring applied at the pivot and merely acting to prevent the handle from dropping freely should it be released by the operator. The fact is, that the particular type of handle-positioning means employed, if any, is not important except in respect to the manner in which the handle is shifted from one position to the other, although it is important to note that the location of the handle pivot is directly above the rear wheels 14. As a consequence, the dead weight of the handle is thrown well to the rear of the center of mass of the cleaner body and hence, it is possible to counterbalance the weight of the cleaner about the rear wheels 14 as a fulcrum, merely by changing the angle of the handle. For example, it may be assumed that by dropping the handle to the lowered position, as shown in Figure 1, the cleaner will tilt backwardly into the dotted line position, whereupon the barrier 27 is raised to a position to permit the converter member to be inserted, as shown in Figure 3.

It is not necessary however, to distribute the weight so nicely as to cause the cleaner to tilt upon its rear wheels merely by shifting the position of the handle, although it is contemplated that the location of the handle pivot will always be such that the weight of the handle plus a slight pressure will tilt the cleaner so that the operator with practically no effort, can easily tilt the cleaner with one hand and insert the converter member with the other. In any case, the tilting of the cleaner body and the accompanying elevation of the nozzle to a height which will insure non-contact of the agitator with the floor covering, must precede the insertion of the converter member preparatory to dusting tool operation. And, once the conversion has been completed, it further follows that the nozzle must remain in elevated position until the dusting tool operation has been completed and the converter member removed. And finally, as heretofore mentioned, while the barrier feature may be applied through hinged rear wheels, the adjustable front wheel and barrier is especially desirable when the handle is mounted near the rear end of the cleaner body.

I claim:

1. In a suction cleaner, the combination of a casing including suction-creating means and a nozzle at its front end communicating therewith through a connecting passage, a port leading into said passage and adapted to receive a converter member for closing off said nozzle and thereby converting said cleaner to off-the-floor operation, front and rear supporting wheels for

said casing, a spring-pressed bracket pivotally mounted on said casing adjacent said port and carrying one of said front wheels, said bracket having a portion normally positioned to obstruct said port but shiftable from port-obstructing position under spring tension in the bodily tilting of said casing backwardly on its rear wheels and in a manner to remove the load from said front wheels.

2. In a suction cleaner, the combination of a 10 casing including a suction-producing unit having a nozzle communicating therewith through a connecting air passage and a port opening into said passage and adapted to receive a converter member carried by a dusting tool hose for closing off 15 the same during off-the-floor cleaning operation, wheels mounted on the underside of said casing, the wheels adjacent said nozzle being carried on brackets pivotally mounted for vertically shifting the position of said wheels to raise and lower said 20 nozzle, the front wheel bracket adjacent said port including a lever arm adapted normally to extend across the entrance to said port to prevent the insertion of said converter member into said port, and tension means acting on said wheel supporting bracket to swing said lever out of port obstructing position, when said casing is tilted about the rear wheels in a direction to raise the nozzle 25 above its normal operating level.

3. In a suction cleaner, the combination of a 30 casing having a fan chamber, a nozzle communicating with said fan chamber through an air inlet passage and a port opening laterally into said passage adjacent the inlet to said fan chamber, a pair of front and rear wheels supporting 35 said casing, said front wheels being mounted for limited vertical movement on pivotally mounted brackets but normally supporting said nozzle at a predetermined distance above the floor surface, one of said brackets having an arm normally 40 adapted to extend transversely of said converter port, and tension means acting on said wheel supporting brackets in a direction to depress said front wheels upon the tilting of said casing backwardly on its rear wheels thereby swinging said 45 lever out of port obstructing position to permit the insertion of a converter member into said port.

4. In a suction cleaner, the combination of a 50 casing having a fan chamber and a nozzle communicating with said fan chamber through an air inlet passage and a port opening laterally into said passage adjacent the inlet to said fan chamber, a pair of front and rear wheels supporting 55 said casing, brackets pivotally mounted on the underside of said casing and carrying said front wheels for limited vertical movement relative to said casing, the front wheel bracket adjacent said converter port having a rearwardly extending arm normally adapted to extend transversely in front of said converter port, abutments contacting said wheel supporting brackets to maintain said nozzle at a predetermined height above the floor, and tension means acting on said pivoted supporting brackets to depress said 60 wheels when said casing is tilted backwardly on its rear wheels and to swing said lever upwardly above the entrance to said converter port, thereby permitting the insertion of a converter member into said port, the subsequent contact of said 65 lever with said converter member acting to maintain said casing in nozzle elevated position.

5. In a suction cleaner, the combination of a 70 casing having a fan chamber and a nozzle communicating with said fan chamber through a con-

necting air passageway, an agitator rotatably mounted in said nozzle, said passage having a port opening exteriorly thereof to receive a converter member, a valve member normally closing 5 said converter port and adapted to be opened by said converter member, pairs of front and rear wheels supporting said casing, said front wheels being mounted for limited vertical movement relative to said casing through the medium of 10 supporting brackets having pivotal connection with the underside of said casing, the pivoted front wheel supporting bracket adjacent said converter port including a lever arm normally extending transversely of said converter port to 15 prevent the insertion of said converter member, abutments coacting with said pivoted wheel supporting brackets to maintain said wheels in a position to support said nozzle at a predetermined height above the floor level, torsion springs acting 20 on said wheel supporting brackets in a direction to depress said wheels upon the tilting of said casing upon the rear wheels as a fulcrum sufficiently to raise the nozzle above its normal height and simultaneously to swing said lever 25 into a position above the converter port thereby permitting the insertion of said converter member, the subsequent forward tilting of the casing bringing said lever into contact with the converter member to hold the cleaner in nozzle 30 elevated position.

6. In a suction cleaner, the combination of a casing including a suction-producing unit and a nozzle communicating with said suction-producing unit through an inlet passage, a rotary agitator mounted in said nozzle, said passage having a port opening thereinto from the exterior thereof adjacent the inlet to said suction-producing unit and adapted to receive a converter member for off-the-floor operation, pairs of 35 wheels mounted adjacent the front and rear ends of said casing, said front wheels being mounted for limited vertical movement at the forward ends of pivoted wheel supporting brackets, abutments on said casing coacting with said wheel supporting brackets to maintain said nozzle at a predetermined height above the floor surface, springs 40

acting on said wheel supporting bracket in a direction to depress said wheels, the spring-actuated front wheel supporting bracket adjacent said converter port having a barrier lever normally extending transversely of the converter port but 5 shiftable in the movement of said supporting bracket under spring tension into a position above and out of port obstructing position upon the backward tilting of said cleaner to permit the insertion of said connector member and to raise 10 the agitator out of contact with the carpet surface, said casing being held in tilted position by the coaction of said converter member with said barrier lever.

7. In a suction cleaner, the combination of a 15 casing including a suction-producing unit and a nozzle communicating with said suction-producing unit through an inlet passage, a rotary agitator mounted in said nozzle, said passage having a port opening thereinto from the exterior thereof adjacent the inlet to said suction-producing unit and adapted to receive a converter member for off-the-floor operation, pairs of wheels mounted 20 adjacent the front and rear ends of said casing, said front wheels being mounted for limited vertical movement through the medium of pivoted wheel supporting brackets, springs acting to press said bracket in a downward direction, the supporting bracket of the front wheel adjacent said converter port having a barrier lever normally 25 extending transversely of the converter port but shiftable from port obstructing position by the tension of said spring upon the removal of the load on said front wheels, and a handle pivotally supported adjacent the rear end of said casing, and means for limiting the swinging movement of 30 said handle rearwardly and downwardly toward a horizontal position, whereby its weight counterbalances the weight carried by said front wheels sufficiently to tilt the cleaner backwardly on its 40 rear wheels thereby raising the agitator out of contact with the carpet surface and displacing said barrier lever to permit the insertion of a connector member into its port.

BERNARD C. BECKER.
